UNITED STATES PATENT OFFICE.

LLOYD ESPENSCHIED, OF KEW GARDENS, NEW YORK.

SOUND RECORDING AND REPRODUCING.

Application filed July 8, 1920, Serial No. 394,708. Renewed May 6, 1927.

The invention relates to the recording and reproducing of sound waves. Its object is to provide recording and reproducing means which are substantially free from distortion and which will enable sound waves to be reproduced with sensibly perfect fidelity.

The invention is concerned particularly with the sound translating devices used to translate between the variations in air pressure characterizing sound waves and waves of some other type. In the phonograph art of today these translating devices function to convert between sound waves and waves of mechanical vibration and are of the familiar diaphragm form. Such diaphragm devices, because of their inherent natural periods, tend to transmit most effectively those component frequencies which resonate with the diaphragm and thereby give rise to distortion of the sound waves.

In accordance with the present invention, the translating device is caused to convert between air waves and electric waves and is of an entirely non-diaphragm type having no appreciable natural period. By thus including in the recording and reproducing processes the intermediate step of conversion of the waves into electric form certain important advantages accrue as elucidated below which enable the distortion to be much reduced. More specifically, the translating device is of a thermal type employing the agency of heat as the connecting link between the air and the electric waves.

A further feature of the invention consists in amplifying the electric waves to the strength required to operate the recording device or the reproducing device as the case may be. The amplification may be such as to enable the recording and reproducing to be effected without the use of a horn. Furthermore, the amplification may be made so great in recording as to permit a recording artist considerable latitude of movement and so great in reproducing as to enable the reproduction to be heard throughout a hall.

Referring now to the drawing forming part of this specification, Fig. 1 illustrates the use of the thermophone as a translating device in a recording system, including the amplifying means and the stylus actuator or recorder proper. Fig. 2 shows the use of another type of resistance-varying translating device—the electric arc—likewise provided with an amplifier and a recorder. Fig.

3 indicates the use of these same or similar means in the reproducing of sound waves from a record.

Referring to Fig. 1, 1 is an air-wave receiving horn, preferably of large flare in order to minimize distortion, to include a number of sound sources or to permit of considerable latitude of movement of the sound source. The horn may be omitted in order to render the sound pick-up substantially non-directional and to minimize reflection effects and their attendant effect upon the sound quality. 2 is the sound-sensitive element, the thermophone. This consists of a very small gauge heat-resisting wire such as platinum. It may be formed by the Wollaston process which consists in drawing down to a small gauge a silver wire with platinum core, and of then dissolving off the silver for a short length, by means of acid, leaving a fine platinum filament. This short section of very fine wire is of small thermal capacity and its resistance follows very rapidly fluctuations in its temperature. Several filaments in parallel, as illustrated, may be used to increase the energy-carrying capacity of the translator. The thermal filament is kept heated, up to say just below a red heat, by the exciting battery 3.

A high-ratio transformer, termed an input transformer, relates the low-impedance circuit of the thermophone with the high impedance input circuit of a vacuum tube or thermionic or audion amplifier shown schematically as 5. This type of amplifier is now well-known in acoustics and communication engineering and not being in itself generic to the present invention is not described in detail. 6 is a second such amplifier operated in tandem with the first. There may be used as many amplifiers as are required for obtaining the electrical energy required to actuate the recording device employed. The last amplifier unit is connected through a step-down output transformer 7 with the recording or scribing device 8.

The recording means 8 is an electromagnetic instrument of the same general type as the familiar telephone receiver. It comprises a shell 9 which supports an annular cap 10 which in turn secures the diaphragm 11. Within the shell is mounted an electromagnet 12, the center core of which carries the usual winding. This winding connects with the output winding of transformer 7 including

the magnetizing or polarizing battery 13. The important feature of this device for the purposes of the invention is that it be highly damped or that it be given a very short (high frequency) natural period, or both. The high damping may be secured by padded members bearing against the diaphragm; or by air-damping by confining by means of a collar 14, a shallow chamber of air behind the diaphragm. The diaphragm is connected with any usual type of stylus arm 15 which may be pivoted, as shown, to cut lateral-wave records.

The operation of the recording system of Fig. 1 is as follows: Sound waves incident upon the heat-sensitive wire 2 vary the resistance of the same and cause current undulations of corresponding frequency in the primary winding of transformer 4. These variations cause alternating potential fluctuations across the secondary winding and between the grid and filament of vacuum tube amplifier 5. The alternations are reproduced in amplified form in the plate-filament output circuit. They are further amplified in like manner in amplifier 6 and pass to the electro-mechanical translating device 8. The diaphragm 11 follows the current variations in the electromagnet and causes the rocking arm 15 to vibrate in corresponding frequency, thus causing the stylus 16 to record undulations in the record 17. It will be understood that the recording device 8 is so mounted in the usual way as to give the crossover feed necessary to carve the record in a spiral groove.

The recording system of Fig. 2 is generally similar to that of Fig. 1 and differs therefrom in respect to the translating device employed in receiving the sound waves and in respect to certain details of the electromagnetic recording instrument. Sound waves entering the horn 1' impinge upon the arc 2' and by virtue of the variations in air pressure characterizing sound waves vary the effective resistance of the arc. The arc is maintained by a direct current source 3' fed through choke coil 20. The fluctuations of the arc resistance in accordance with the sound waves cause corresponding variations in the potential acting across the condenser 21 and primary of transformer 4'. These alternating potentials and resulting currents are amplified by amplifiers 5' and 6', and operate the recording device 8'. This device differs from the corresponding one 8 of Fig. 1 in that the diaphragm 11', is made of parchment stretched over an annular support 19. The object of this construction is to impart a high natural frequency to the diaphragm to bring this frequency above the acoustic range of ordinary sounds, and thereby obviate distortion arising from the natural period being within the working frequency range. Diaphragm 11 is pro-

vided with a ferric armature 18 made as thin and light weight as possible. The vibrations imparted to the diaphragm system by the electromagnet 12' are transmitted to stylus 16' through arm 15' and are traced in the record 17' in the usual way.

In the recording devices 8 and 8' are represented two ways of obviating distortion in such electromagnetic devices, one by means of high damping as in the case of 8, and the other high natural frequency as in the case of 8'. It will be understood that these translating devices whose function it is to translate between electric and mechanical wave motion are not limited to the electromagnetic type, but may be of other types such as the electrostatic in which case a condenser plate is controlled by the charge impressed upon it and effects the motion of the stylus. Furthermore the record may be of the telephone type and the translator the magnetizing electro-magnetic. In the case of recording photographically by controlling a beam of light in accordance with the sound waves, the recording translator may be a source of light, the brilliancy of which is controlled by the output current of the amplifier. For recording by the light method, the same circuit as is employed in Fig. 2 for air-electric translation may be duplicated on the output side of amplifier 6', in lieu of the electromagnetic translator 8'. The light source may be an arc light similar to 2' with its two circuits, the direct current supply and the sound-frequency circuit, represented by the condenser 21 and primary winding of transformer 4'. In this case the light-intensity of the arc is modulated by the sound-wave currents and the recording is effected without the use of any diaphragm device whatsoever.

The steps involved in the recording systems above described are those of (1) air-electric translation by non-diaphragm translators, (2) amplification and (3) translation onto the record. This same sequence of functions may be operated in reverse manner for the purpose of reproducing a record. This fact is indicated in Fig. 3 where the amplifiers 5'' and 6'', corresponding to those of the previous figures, are shown reversed in their position in the circuit. Both of the two types of translating devices of Figs. 1 and 2 are reversible in their action and need not be redrawn in Fig. 3. The operation in reproducing a record is that the record, upon being played, generates electric currents in the electromagnetic translating device (8 or 8'); these currents are amplified and the amplified currents actuate the thermal electric-air translators (2 or 2') and create sound waves. The variations in the heat developed by the thermal element (of either 2 or 2') cause variations in the immediately surrounding

air pressure and these variations propagate outward as reproductions of the original sound waves.

My invention will now be appreciated to reside in the method of operation and in the combination of parts comprising the system whereby it is possible to record and reproduce sound waves substantially without distortion. The several elements which characterize the invention are as follows:

1. The air-electric translating device; this being primarily an element in the electric circuit the resistance of which is controlled directly by the air waves as distinguished from being controlled indirectly by means of a diaphragm as in the ordinary telephone transmitter.

2. The record-taking or reproducing means which is rendered substantially distortionless and which may be mechanical, magnetic, light or other type depending upon the form of record employed.

3. The amplifier whereby the waves are amplified to the desired volume and which overcomes the reduced efficiency of the high quality translating devices.

It will be appreciated that many variations are possible in the arrangements and devices employed for recording and reproducing sound waves, without departing from the spirit and scope of the invention as defined in the claims.

What I claim as new and desire to secure by Letters Patent is:

1. In a phonograph system for translating sound waves without sensible distortion, the combination of an electric transmission circuit, a device for translating sound waves between the circuit and the record, said device comprising an operating member having a natural period of vibration substantially higher than the frequencies of vibration to be translated thereby, and a substantially non-distorting non-diaphragm type of device for translating between the sound waves in the air and the electric circuit.

2. In a phonograph system for translating sound waves without sensible distortion, the combination of an electric transmission circuit, a device for translating sound waves between the circuit and the record, said device comprising an operating member having a natural period of vibration substantially higher than the frequencies of vibration to be translated thereby, a substantially non-distorting non-diaphragm type of device for translating between the sound waves in the air and the electric circuit, and a substantially distortionless electronic type of amplifier included in said electric circuit.

3. In a phonograph system for translating sound waves without sensible distortion, the combination of an electric circuit, means for converting air waves into electric waves in said circuit, said means comprising a translating device, the electric resistance of which is controlled directly by the air waves without the intervention of a vibrating member, means in said circuit for amplifying said waves, and an electromagnetic device for recording said waves, said device being substantially equally responsive to all frequencies in the range to be recorded thereby.

4. In a phonograph system for translating sound waves without sensible distortion, the combination of an electric circuit, means for converting air waves into electric waves in said circuit, said means comprising a resistance element sensitive directly to sound waves impinging thereon, and including a source of electric current, means in said circuit for amplifying said waves, and an electromagnetic device for recording said waves, said device being substantially equally responsive to all frequencies in the range to be recorded thereby.

In testimony whereof, I have signed my name to this specification this sixth day of July, 1920.

LLOYD ESPENSCHIED.
